UNITED STATES PATENT OFFICE.

EDWARD B. GADSEY AND GEORGE P. DORRIS, OF ST. LOUIS, MISSOURI.

GEAR-CONTROLLING DEVICE FOR MOTOR-VEHICLES.

No. 821,161.

Specification of Letters Patent.

Patented May 22, 1906.

Application filed October 5, 1904. Serial No. 227,207.

To all whom it may concern:

Be it known that we, EDWARD B. GADSEY and GEORGE P. DORRIS, citizens of the United States, residing in the city of St. Louis, in the State of Missouri, have invented certain new and useful Improvements in Gear-Controlling Devices for Motor-Vehicles, of which the following is a full, clear, and exact description, reference being had to the accompanying drawings, forming part of this specification.

Our invention relates to a device through the medium of which the gearing of a motor-vehicle may be quickly and efficiently altered to provide for direct driving action with respect to the engine-shaft and also to provide for change of speed through alteration in the association of the gear members.

Our invention consists in features of novelty hereinafter fully described, and pointed out in the claims.

Figure I is a longitudinal section taken through the gearing of a motor-vehicle and showing our improvement applied thereto. Fig. II is a vertical cross-section taken on line II II, Fig. I, looking in the direction of the arrow at said line. Fig. III is a vertical cross-section taken on line III III, Fig. I. Fig. IV is a cross-section taken on line IV IV, Fig. I, looking in the direction of the arrow at said line. Fig. V is a cross-section taken on line V V, Fig. I, looking in the direction of the arrow at said line. Fig. VI is a perspective view of the bell-crank rocker carried by the clutch-controlling foot-lever of a motor-vehicle. Fig. VII is a perspective view of the notched forward end of the shift-gear-controlling rod.

1 designates the gear-casing, in which the gearing of a motor-vehicle is mounted in a common manner. No invention *per se* is herein claimed for this gearing; but it will be sufficiently described to provide for an understanding of the application of our improvement thereto.

2 designates the driven shaft, which passes longitudinally through the casing 1, being mounted in suitable bearings.

3 is a gear-wheel shaft that is journaled in suitable bearings mounted in the casing 1, the shaft 3 being arranged in a line parallel with the shaft 2. Fixed to the shaft 3 is a transmission gear-wheel 4, low-speed gear-wheels 5 and 6, and a reversing-pinion 7.

8 is a sleeve loosely mounted on the forward end of the driven shaft 2. This sleeve

carries at its rear end a gear-head 9, that is constantly in mesh with the transmission gear-wheel 4, and on the rear face of said gear-head are clutch-teeth 10. (See Fig. IV.) At the outer end of the sleeve 8 and integral therewith is a driven clutch-disk 11.

13 is a clutch-ring slidably keyed on the hub 11' of the clutch-disk 11.

15 is a clutch-driving member having the web thereof positioned between the friction-rings 12 and 14. This driving member is designed to receive power from a suitable motor.

16 is a grooved slide-collar mounted on the sleeve 8 and backed by a coil-spring 17, the tendency of the action of which is to force the slide-collar in a direction toward the clutch just described.

18 is a collar fixed to the clutch-disk hub 11', and 19 represents rockers, each having one end projecting toward the clutch-ring 13 and having loosely mounted in the other end a roller 20, that normally rests against the perimeter of the slide-collar 16. When the slide-collar 16 is moved outwardly on the sleeve 8, either by manual action or under the action of the spring 17, said collar rides between the rollers 20 and swings the rocker 19 to force the clutch-disk 13 outwardly to frictionally clamp the driving member 15 between the clutch members 11 and 13, and when the collar 16 is reciprocated rearwardly the rockers are freed, so that the clutch members 11 13 are rendered inactive, so that the driving member 15 may rotate between them without driving action.

21 is a reciprocating gear member slidably mounted on the driven shaft 2, and that includes a gear 22, arranged for engagement with the low-speed gear-wheel 5, and a large gear 23, arranged for engagement with the low-speed gear-wheel 6 on the shaft 3.

24 represents clutch-teeth carried by the forward end of the gear member 21 and arranged for engagement with the clutch-teeth 10 when said member is reciprocated on the driven shaft toward the inner end of the sleeve gear-head 9.

25 (see Fig. II) is a gear-wheel mounted on a shaft 26 independently of the shafts 2 and 3 and arranged in mesh with the gear 23 of the member 21, this gear-wheel 25 being an intermediate gear and meshing with the reversing-pinion 7 to impart retrograde rotation to the shaft 3, which is transmitted through the transmission gear-wheel 4 to the

sleeve 8 and the driving-clutch member 15, carried thereby.

27 designates a yoke that is fitted to the gear member 21.

5 28 is a reciprocating throw-rod that extends longitudinally through the rear end of the casing 1 and through the upper end of the yoke 27, the said rod being provided with a nut 29, that bears against the rear face of said yoke. The rear end of the throw-rod has united to it a coupling 30, that leads to a lever 31, pivotally supported at 32 intermediate of its ends, and connected to said lever at the opposite end from that to which the 15 throw-rod 28 is connected is an operating-rod 33, that leads to a hand-lever 34.

35 designates a controlling-bar carried by the throw-rod 28 and extending forwardly from the yoke 27. This controlling-bar is 20 provided in its upper side with a series of notches 36, 37, 38, and 39, (see Figs. I and VII,) the said bar being extended through the forward end of the casing 1, as seen in Fig. 1.

25 40 designates a foot-lever that is supported by a rocker-shaft 41, pivotally mounted in a bracket 42, surmounting the gear-casing 1.

43 is a bell-crank rocker having a horizontal rearwardly-extending arm 44 and a downwardly-extending arm 45, the said rocker being fixed to the rock-shaft 41 at the junction of its arms, as seen most clearly in Fig. VI. The rocker-arm 45 is provided at 35 its lower end with fork-arms 46, that straddle the slide-collar 16 and are furnished with studs 47, that enter the groove in said collar.

48 is a roller journaled to the rear end of the horizontal rocker-arm 44 and arranged to 40 enter into either of the notches in the controlling member 35 when said controlling member is shifted longitudinally thereunder.

49 is the operating-rod, leading from the foot-lever 40 to the brake mechanism of a 45 motor-vehicle. (Not shown.)

In the practical use of our improvement the operation of the parts is as follows: When the parts are in the position shown in Fig. I, in which the gear 22 of the gear member 21 50 is in mesh with the low-speed gear-wheel 5, the power from the driven shaft 2 is conducted to the gear-wheel shaft 3 and transmitted by transmission-gear 4 to the sleeve 8 on the driven shaft through the medium of the 55 gear-head 9. During the rotation of the sleeve 8 the clutch-driving member 15 may be thrown into or out of action, as desired, upon the actuation of the foot-lever 40 and the bell-crank rocker 43. At the time that 60 the gear 22 is in mesh with the low-speed gear-wheel 5 the roller 48, carried by the bell-crank-rocker arm 44, rests in the notch 37 of the controlling-bar 35.

Should it be desired to throw the driven 65 shaft into direct driving engagement with the

sleeve 8, the hand-lever 34 is thrown rearwardly, thereby reciprocating the operating-rod 30 and imparting forward reciprocation to the throw-rod 28 through the medium of the lever 31. When this is done, the controlling-bar 35 is reciprocated forwardly to carry the notch 36 therein into a position beneath the rocker-carried roller 48, during which movement the roller rides over the crown between the notches 37 and 36, and 70 the forked rocker-arm 45 causes rearward reciprocation of the slide-collar 16 to throw the clutch-driving member out of action. The forward reciprocation of the throw-rod and controlling-bar causes like movement to 75 be imparted to the gear member 21, with the result that the clutch-teeth 24, carried by said member, are moved into engagement with the clutch-teeth 10 of the gear-head 9, and therefore a positive connection of said members is 80 obtained for the direct driving of the clutch-carrying sleeve. Should it be desired to obtain a low speed in the gearing, the hand-lever 34 is thrown forwardly instead of rearwardly, with the result that the controlling- 85 bar 35 is reciprocated rearwardly to carry the notch 38 therein to the roller 48, so that said roller will rest therein, and when this is done the large gear 23 of the gear member 21 90 is placed in mesh with the gear-wheel 6 on the gear-shaft 3. To reverse the action of the gearing, the controlling-bar 35 is reciprocated rearwardly to a sufficient extent to carry the notch 39 to the roller 48, and as a consequence of such extreme movement the 95 gear 23 is carried into mesh with the intermediate gear 25 to occasion reverse rotation of the gear-shaft 3 through the medium of the reversing-pinion 7, so that retrograde rotation will be transmitted to the clutch-carry- 100 ing sleeve 8.

When the brake mechanism is to be thrown into action, the foot-lever 40 is pressed forwardly, thereby throwing the downwardly-extending rocker-arm 45 rearwardly to retract the slide-collar 16 and render the clutch members 11 and 13 inactive, and at the same time a pull is effected upon the brake-operating rod 49, during which action the rocker-arm 44 is elevated to raise 115 the roller 48 out of either of the notches in the controlling-bar in which it was seated; but the controlling-bar is unaffected by such movement, and therefore said roller returns to its former position to hold the controlling- 120 bar as before without the gearing in its previously-set condition being disturbed. This actuation provides for the throwing of the clutch out of action and applying the brake to the vehicle in one operation.

125 We claim as our invention—

1. In a gear-controlling device for motor-vehicles, the combination with a changeable gearing of the character described, of a spring-controlled clutch, a reciprocatory 130

- notched bar secured to a part of said gearing, a single lever for changing the gearing and reciprocating said bar, and means for releasing said clutch when the gearing is changed; 5 said means comprising a bell-crank rocker having one of its arms connected to the clutch and having its other arm adapted to ride on said notched bar for vertical reciprocation thereon when the bar is reciprocated.
- 10 2. In a gear-controlling device for motor-vehicles, the combination with a changeable gearing of the character described, of a spring-controlled clutch, a reciprocatory notched bar secured to a part of said gearing,
- a single lever for changing the gearing and 15 reciprocating said bar, and means for releasing said clutch when the gearing is changed; said means comprising a bell-crank rocker having one of its arms connected to the clutch and having a roller on its other arm 20 adapted to ride on said notched bar for vertical reciprocation thereon when the bar is reciprocated.

EDWARD B. GADSEY.

GEORGE P. DORRIS.
